MATERIAL FOR MANUFACTURING PAPER COLLARS AND THE LIKE

Wilhelm Müller and Adolf Closmann, Leipzig,
Germany, assignors to Atlas Ago Chemische
Fabrik, Aktien-Gesellschaft, Molkau, near Leip-
zig, Germany, a corporation of Germany

No Drawing. Application February 17, 1936, Se-
rial No. 64,343. In Germany November 25,
1935

6 Claims. (Cl. 154—46)

The present invention relates to a material for manufacturing articles of clothing and, more particularly, to a material for manufacturing paper collars and the like and to a process of preparing such material.

Heretofore, clothing, collars and the like made of a paper base could not successfully compete with the considerably more expensive linen clothing. The principal reason of the inadequacy of conventional paper collars and the like was that during their preparation and use they quickly became brittle. Due to this brittleness the articles of clothing made of a paper base developed cracks which accelerated their destruction by perspiration and other external influences and caused the articles to be quickly soiled and to become unsightly. Thus, the lower initial cost of paper articles of clothing was more than outweighed by the cost of frequent replacement and by their poor and readily recognizable cheap appearance. Although the manufacture and sale of conventional paper collars and the like survived, the scope of the industry remained a necessarily restricted one, in view of the fact that the public did not approve the conventional paper clothing articles and persons of particular taste refused to use and to wear the same.

It has already been suggested to cover sheets of paper or of cardboard with linen and to use the composite sheet provided in this manner for the manufacture of collars and the like articles of clothing. The provision of a linen surface reduced the disadvantages of the paper article to a certain limited extent. On the other hand, however, the raw materials and the process of preparing these combined paper-linen articles was costly so that the advantage of low manufacturing price was in part destroyed. Although many other suggestions and proposals have been made from time to time and demonstrated the interest the art has taken in the problem, none, as far as we are aware, of these various suggestions and proposals has been completely satisfactory and successful when carried into practice on a commercial scale.

It has been discovered that the present problem may be solved in a remarkably simple manner.

It is an object of the present invention to provide a composite material or sheet for the manufacture of paper collars and the like articles of clothing which is free from the disadvantages of conventional materials and which does not develop brittleness, breaks, cracks, and the like during processing and wearing.

It is another object of the present invention to

provide a composite material of resilient and non-breaking character comprising a base and a covering layer of different mechanical properties which is capable of taking a linen-like exterior finish and which permits the manufacture of 5 collars and the like having the appearance and the wearing qualities of real linen articles.

The invention also contemplates the provision of a sheet-like composite material closely approaching the surface appearance and the 10 strength of linen, which may be readily manufactured at a low cost on a practical and commercial scale.

Other and further objects and advantages of the present invention will become apparent from 15 the following description.

According to the principle of the invention, a base of paper-like character is provided having relatively long fibres embedded therein and which have a strong, tough character but are capable 20 of yielding to pressure without being permanently deformed and without incurring permanent "sets". A non-breaking and non-tearing covering layer is provided on the base thus prepared which is firmly bonded to the base. It is preferred to 25 provide a top layer on this composite sheet by means of a cementitious agent such as glue, gelatinous material, a lacquer, a film layer, or the like. It is also possible to reinforce, or to densify the upper half of this soft cardboard by means 30 of a subsequent gluing or impregnation process of various character. As those skilled in the art know, this may be accomplished in a number of different ways. It is essential, however, that a strong and dense covering layer should be provided on a relatively soft and yielding base. The bending and breaking strength of the different layers constituting the material have to be different, more particularly, the external or upper layer has to have the greater strength.

On two different paper-engines two cardboards are separately produced from long cellulosic fibres. These cardboards must be clearly white. They are sized and pressed in a different degree so that the one layer is softer and more yielding than the other which is strong and dense. The 2 layers are united by means of an adhesive substance, preferably in such a way that the fibres of the 2 layers are crossed to each other. This composite sheet may now be impressed with a pattern 50 of linen-like surface formation. Thereafter it is coated with a top layer of lacquer which consists of a mixture comprising 10% nitrocellulose of high viscosity, 81% ethylacetate, 2% dibutyl-phthalate, 3% tributylphosphate, 4% blown castor 55

oil. As a pigment or filler, titanium dioxide is added in a quantity amounting to about 10 to 20% of the total quantity of the above mixture. When the coating is dried, collars may be stamped out of the material in such a form that they may be directly used as clothing.

The material is preferably used in a thickness of 0.25-0.55 mm.

The coating lacquer has the additional purpose of giving a pure white or colored finish to the article and of making the surface washable and resistant to perspiration. The lacquer has to contain such addition agents which permit binding of large amounts of a suitable pigment without becoming fragile or brittle. This is necessary, because if the quantity of pigment embodied is insufficient, the finished product has an undesirable "fatty" gloss. Moreover, the lacquer has to be of a very firmly adhering and resilient character because if the lacquer is brittle, it is incapable of resisting to the stresses of sharp bending which are unavoidable during preparation and use of the finished article. The addition agents have to be of such character that they do not cause or promote yellowing or discoloration of the surface. It has been found that tributyl phosphate, for example, is a very satisfactory addition agent.

As shown above in the preparation of the lacquer preferably a highly viscous collodion cotton is used which provides a lacquer layer having the required mechanical properties. A lacquer prepared of collodion cotton and of dibutyl-phthalate, tributyl phosphate, blown oil and titanium oxide as addition and filling agents has been found to be especially satisfactory.

In order to improve the linen-like surface appearance it is preferable to impress the sheet with a suitable pattern of linen-like character after it has been coated with a top layer of lacquer.

It is noted that according to the principles of the invention a material for manufacturing collars and the like articles is provided which in the finished product or article cannot be distinguished from the real linen article with regard to its appearance or wearing qualities.

It is also to be observed that collars made of the material prepared according to the principles of the invention have a strong, attractive surface formation comparative to that of linen which may be washed and which does not become rough or "woolly" in appearance.

It is also to be noted that the material according to the present invention is capable of being manufactured on a commercial and industrial scale at a very low price and permits the production of collars and similar articles which are capable of satisfying the most exacting taste.

Although the present invention has been described and explained in connection with a practical embodiment thereof many variations and modifications are possible without departing from the principles of the invention. All of these variations and modifications are considered to be within the true spirit and scope of the present invention as disclosed in the present specification and defined by the appended claims.

We claim:

1. As a new article of manufacture, a paper collar having an appearance closely similar to that of linen collars and being free from brittleness and telltale wrinkles characteristic of conventional paper collars comprising a body consisting of a soft and yielding base of fibrous cel-

lulosic material having relatively long fibres embedded therein forming the inner surface of said collar, and a strong and dense fibrous cellulosic covering layer firmly bonded to said base forming the outer surface of said collar, said collar being free from brittleness and being adapted to be subjected to sharp bending without wrinkling and cracking.

2. As a new article of manufacture, a paper collar and the like having an appearance closely similar to that of linen collars and being free from brittleness and telltale wrinkles characteristic of conventional paper collars comprising a resiliently yielding fibrous cellulosic base forming the inner surface of said collar, and a covering layer of fibrous cellulosic character firmly bonded to said base forming the outer surface of said collar and having substantially greater strength than said base, the fibres of said base and of said covering layer being crossed to each other, said collar being free from brittleness and being adapted to be subjected to sharp bending without wrinkling and cracking.

3. As a new article of manufacture, a paper collar having an appearance closely similar to that of linen collars and being free from brittleness and telltale wrinkles characteristic of conventional paper collars comprising a relatively soft and resiliently yielding fibrous cellulosic base forming the inner surface of said collar, a strong and dense fibrous cellulosic covering layer firmly bonded to said base forming the outer surface of said collar, the fibers of said base and of said covering layer being crossed to each other, and a top layer of lacquer having a cellulosic ester base on said dense covering layer, said collar being free from brittleness and being adapted to be subjected to sharp bending without wrinkling and cracking.

4. As a new article of manufacture, a paper collar having an appearance closely similar to that of linen collars and being free from brittleness and telltale wrinkles characteristic of conventional paper collars comprising a body consisting of a base of relatively soft and resiliently yielding fibrous cellulosic material forming the inner surface of said collar, a strong and dense fibrous cellulosic covering layer bonded to said base forming the outer surface of said collar, and a top layer of lacquer on said dense covering layer and having a firmly adhering and resilient character and containing an addition agent which permits binding of large amounts of a suitable pigment without becoming brittle, said collar being free from brittleness and being adapted to be subjected to sharp bending without wrinkling and cracking.

5. As a new article of manufacture, a paper collar having an appearance closely similar to that of linen collars and being free from brittleness and telltale wrinkles characteristic of conventional paper collars comprising a body consisting of a relatively soft and yielding fibrous cellulosic base forming the inner surface of said collar, a strong and dense fibrous cellulosic covering layer bonded to said base forming the outer surface of said collar, and a top layer of lacquer on said dense covering layer and consisting of a base of collodion containing tributyl phosphate, a blown oil and titanium oxide as addition and filling agents, said collar being free from brittleness and being adapted to be subjected to sharp bending without wrinkling and cracking.

6. As a new article of manufacture, a paper collar having an appearance closely similar to

that of linen collars and being free from brittleness and telltale wrinkles characteristic of conventional paper collars comprising a relatively soft and yielding base of fibrous cellulosic material having relatively long fibres embedded therein forming the inner surface of said collar, a strong and dense fibrous cellulosic covering layer firmly bonded to said base forming the outer surface of said collar, the fibers of said base

and of said covering layer being crossed to each other, and a top layer of lacquer on said dense covering layer having a cellulose ester base impressed with a pattern of linen-like surface formation, said collar being free from brittleness and being adapted to be subjected to sharp bending without wrinkling and cracking.
